POWER CYLINDER FOR INTERNAL COMBUSTION ENGINES

Frank H. Kelley, Cumberland, Md.

Application April 8, 1940, Serial No. 328,554

1 Claim. (Cl. 123—193)

This invention relates broadly to internal combustion engines and more particularly to a power cylinder construction and assembly therefor.

An object of the present invention is to provide a power cylinder, power piston, and cylinder head arrangement having a greater valve capacity for increasing the intake and exhaust of the cylinder to the end that maximum power with minimum fuel consumption will result; and whereby less wear and distortion of the cylinder and piston will minimize reboring and replacement of piston rings.

The invention together with its objects and advantages will be best understood from a study of the following description taken in connection with the accompanying drawing wherein:

Figure 1 is a vertical sectional view through a power cylinder and head therefor, with the power piston and intake and exhaust valves shown in elevation.

Figure 2 is a view taken substantially on the line 2—2 of Figure 1 and looking in the direction of the arrows.

Figure 3 is a view taken substantially on the line 3—3 of Figure 1 and looking in the direction of the arrows.

Referring more in detail to the drawing it will be seen that in accordance with the present invention the power cylinder 5, instead of, as is conventional, being round, is substantially elliptical in top plan and cross-section and the piston 6 having a working fit therein is of a shape complementing the said shape of the power cylinder. However, as shown the cylinder and piston are each formed of flattened sides and rounded ends. When a number of cylinders is placed in a block the cylinders will extend longitudinally of the block and they will have their greater diameters parallel to the longitudinal axis of the block and also parallel to the crankshaft.

For the cylinder 5 there is provided a head 7 that in edge contour will complement the shape of the power cylinder 5.

The head 7 is provided with the fuel intake port 8 and exhaust port 9, ports 8 and 9 being provided at the inner ends thereof with seats 10 to accommodate the disk valves 11 and 12 respectively, and which are otherwise of conventional structure.

The advantages of this invention will be apparent from the following:

A cylinder and piston having the shape contemplated by the present invention will have approximately the same area as that of the conventional round power cylinder and power piston. However, with a cylinder constructed in accordance with this invention larger valves

can be used than are used with round cylinders and the valve arrangement is more compact than with round cylinders and most of the expanding gases are over the piston.

With this greater valve capacity resulting from the shape contemplated by the present invention, the fuel can be drawn into the power cylinder and the exhaust gases discharged therefrom with more rapidity to the end that the revolutions per minute may be increased without resulting in a decrease in efficiency.

Also, a power cylinder having the design contemplated by the present invention will reduce cylinder distortion because the wear is distributed over a greater area of surface both as regards the wall of the cylinder and the body of the piston.

It will also be found that with a cylinder embodying the features of the present invention airplane engines of the radial type could be equipped with at least one-third more additional cylinders, thus increasing displacement with consequent result of more even flow of power, better cooling, and reduction of wind resistance.

It will also be understood that a piston and cylinder having a shape contemplated by the present invention will result in the greater expansion of the piston in the direction of the greater radial dimension of the cylinder and piston, thus allowing for greater piston clearance.

It is thought that the invention, together with its advantages, will be clearly appreciated by those skilled in the art from the foregoing, and that accordingly a further detailed description thereof is unnecessary.

Having thus described the invention what is claimed as new is:

In an engine of the class described, a block having a cylinder therein, said cylinder having flat sides and outwardly bowed ends, a crankshaft below the cylinder, the long diameter of the cylinder being parallel to the crankshaft, a piston in the cylinder of the same shape as the cylinder, a rod connecting the piston with the crankshaft, a head for the block having a combustion chamber therein of the same shape and size as that of the cylinder, said head having inlet and exhaust passages in communication with the combustion chamber and inlet and outlet valves controlling such passages, said valves being located directly over the piston, the inlet passage having a portion located adjacent and concentric to one end of the combustion chamber, and the exhaust passage having a part located adjacent and concentric to the other end of the combustion chamber, and said combustion chamber forming a continuation of the cylinder.

FRANK H. KELLEY.
